UNITED STATES PATENT OFFICE

MORRIS TEPLITZ, OF KANSAS CITY, MISSOURI, ASSIGNOR TO CORONA CONVERSION CORPORATION, OF KANSAS CITY, MISSOURI, A CORPORATION OF ARIZONA

PROCESS OF REFINING MINERAL OILS

Application filed November 18, 1925. Serial No. 69,917.

This invention relates to processes of refining mineral oils; and it has to do more particularly with the refining of mineral oils which are characterized by a substantial content of gum-forming unsaturates, often in company with impurities, such as sulfur, causing poor color and disagreeable odor. The invention is concerned especially with the treatment of cracked hydrocarbon distillates, particularly cracked gasolines, which often contain gum-forming olefins or other unsaturates, sulfur, and the like.

As the invention is of greatest present utility in the treatment of cracked hydrocarbon motor fuels derived from petroleum or other mineral oils by so-called cracking or converting methods of various kinds, that phase of the invention will be more particularly referred to hereinafter in explaining the principles upon which the invention rests. This is not to be understood, however, as intended to limit the scope of the invention which is of general applicability to the refining of mineral oils.

It has been the practice heretofore to treat gasolines and other mineral oil distillates, where these contain substantial proportions of unsaturated compounds, especially those of gum-forming properties, with strong sulfuric acid to remove such compounds as a sludge. Such methods of treatment, involving not only treatment with acid but also subsequent treatments with alkali, washing, etc., to bring the product to good color and odor, and to the necessary degree of neutrality, are not only troublesome and expensive to carry out but they also occasion considerable loss of the gasoline or other distillate treated. It is one of the principal objects of the present invention to enable mineral oils, particularly gasolines and other petroleum distillates, to be refined and brought to a condition of good color and stability while avoiding the difficulties and losses characterizing the refining methods of the prior art.

Generally described, the process of the present invention comprises first chlorinating the mineral oil to be refined by means of a suitable chlorinating agent which may be either free chlorine or a compound containing

or yielding chlorine in available form, and then subjecting the chlorinated mineral oil in heated condition, either in liquid or vapor form, or both, to the action of a de-chlorinating agent which may desirably be a de-chlorinating metal, especially zinc, and recovering a finished mineral oil product of improved characteristics as the result of such treatment. In order to afford a full understanding of the principles underlying the invention, one way in which it may be successfully practiced will be hereinafter described in detail as an illustrative example, reference being also had to the accompanying drawing which shows in side elevation, more or less diagrammatically, suitable apparatus which may be used in carrying out the process.

In the typical embodiment of the new process to be described by way of example, it will be assumed that the mineral oil to be refined is a cracked mineral oil distillate of about 52 Bé. gravity, containing in the neighborhood of 12 per cent of olefins by the usual methods of estimation and giving a positive doctor test for sulfur. The color of this crude distillate is a canary yellow. A quantity of this distillate to be refined is run into a suitable tank or other container (not shown) and chlorin gas is passed into it until the color begins to darken perceptibly, indicating, in the case of this particular distillate, that a sufficient amount of chlorin has been bubbled through to effect chlorination to the desired extent. A further quantity of chlorin may be passed into the distillate as a precautionary measure, but ordinarily this will be found unnecessary.

The gasoline thus chlorinated is next introduced into a still indicated at 10 in the drawing and heated in the usual way to effect distillation, the vapors leaving the still through vapor off-take 11 and entering the base of a dephlegmating fractionating tower or column 12 packed with a de-chlorinating metal 13 in granular or other fragmentary form so that the mass is permeable by the oil vapors. Zinc is an especially effective de-chlorinating metal to employ in the column. High-boiling constituents of the vapors condense and may either be returned to the still

through run-back line 12^a or directed elsewhere. The remaining hot oil vapors pass up through the mass of zinc and then leave the purifying tower through pipe 14 which conveys the purified vapors to a condenser 15 where gasoline condenses as a liquid and passes through look-box 16 and line 17 to a suitable run-down tank. The zinc favors elimination of chlorine and assists in effecting stabilization of the unsaturates and in the removal of sulfur. Sulfur is also removed by the zinc. The purified gasoline thus obtained may advantageously receive an alkaline wash, as with caustic soda solution, to remove any traces of free chlorin that may be present, after which it is marketable as finished gasoline. The product possess good color and odor, gives a negative test with doctor solution and is substantially stable.

The foregoing method of treatment may be modified to advantage in many cases by ensuring the presence of an added hydrogenating gas or vapor (the term gas being used generically to include either gas or vapor or both) in mixture with the vapors of the oil distilled from still 10 and passing through the packed column 12. To this end natural gas, most desirably preheated, for example, may be introduced into the still through inlet 18 during the distillation, the hot mixture of oil vapors and natural gas then passing through the packed column where the zinc acts to remove chlorin from the chlorinated gasoline while the resulting nascent unsaturated hydrocarbons react, together with the methane and other constituents of the natural gas, to form saturated compounds.

In some cases it is found advisable to supply additional heat to the vapors passing through the mass of dechlorinating material in the dephlegmating tower 12. Thus, in refining some types of crude distillates in accordance with the invention, light vapors distil over at temperatures insufficiently high for most effective action of the de-chlorinating agent employed in the tower. Accordingly said tower may advantageously be provided with suitable heating means of appropriate character for raising the temperature of the vapors in the tower when this is necessary or advisable. In the present example such heating means is shown as comprising a jacket or housing 18 through which a heating medium, such as hot furnace or flue gases, for instance, may be passed.

While, in the specific example described hereinabove, the chlorinated oil is exposed in vapor form to the action of the de-chlorinating metal, it is feasible to place the de-chlorinating metal in the still with the chlorinated oil to be refined, and then to distil either with or without introducing natural gas or other hydrogenating gas into the still.

Where necessary or advisable, the resultant distillation vapors may also be subjected to the action of a de-chlorinating agent to remove residual chlorine.

What is claimed is:

1. The process of refining mineral oils containing unsaturates which comprises chlorinating such a mineral oil, and subjecting the chlorinated oil to heat in the presence of zinc. 70

2. The process of refining mineral oils containing unsaturates which comprises chlorinating such a mineral oil, distilling the chlorinated oil, and contacting the hot distillation vapors with zinc. 75

3. The process of refining mineral oils containing unsaturates which comprises chlorinating such a mineral oil, and subjecting the chlorinated oil to heat in the presence of zinc and a gaseous hydrogenating agent. 80

4. The process of refining mineral oils containing unsaturates which comprises chlorinating such a mineral oil, distilling the chlorinated oil, and subjecting the hot distillation vapors in mixture with a gaseous hydrogenating agent to the action of zinc. 85

5. The process of refining a cracked mineral oil distillate which comprises chlorinating such a distillate, and subjecting the chlorinated distillate to heat in the presence of zinc. 90

6. The process of refining a cracked mineral oil distillate which comprises chlorinating such a distillate, and subjecting the chlorinated distillate to heat in the presence of zinc and a gaseous hydrogenating agent. 95

7. The process of refining crude gasoline containing unsaturates which comprises passing chlorine into such gasoline, and subjecting the thus treated gasoline to heat in the presence of zinc. 100

8. The process of refining crude gasoline containing unsaturates which comprises passing chlorine into such gasoline until sufficient chlorination is effective, distilling the thus treated gasoline, passing the hot distillation vapors through a permeable mass of zinc, and condensing gasoline from the effluent vapors. 110

9. The process of refining crude gasoline containing unsaturates which comprises passing chlorine into such gasoline until the color thereof darkens, distilling the thus treated gasoline, passing the hot distillation vapors in company with an added hydrogenating gas through a permeable mass of zinc, and condensing gasoline from the effluent vapors. 115

10. The process of refining crude gasoline containing unsaturates which comprises passing chlorine into such gasoline until the color thereof darkens, distilling the thus treated gasoline, passing the hot distillation vapors in company with natural gas through a permeable mass of zinc, and condensing gasoline from the effluent vapors. 125

11. The process of refining mineral oils containing unsaturates which comprises chlorinating such a mineral oil, and thereafter subjecting the chlorinated oil to heat in the presence of a metallic de-chlorinating agent comprising zinc.

12. The process of refining mineral oils containing unsaturates which comprises chlorinating such a mineral oil, and distilling the chlorinated oil in the presence of a metallic de-chlorinating agent comprising zinc.

13. The process of refining unstable mineral oils which comprises passing chlorine into such a mineral oil, distilling the oil in the presence of a metallic agent comprising zinc, and subjecting the resultant distillate to an alkaline wash to remove residual traces of free chlorine.

14. The process of refining cracked mineral oil distillates to stabilize the same which comprises passing chlorine into such a distillate, redistilling said distillate in the presence of a metallic agent comprising zinc, and subjecting the resultant distillate to an alkaline wash to remove residual traces of free chlorine.

In testimony whereof I hereunto affix my signature.

MORRIS TEPLITZ.
